[57] CLAIM

The ornamental design for a pipe, as shown.

DESCRIPTION

FIG. 1 is a top plan view of a pipe showing my new design;

FIG. 2 is a back elevational view thereof;

FIG. 3 is a side elevational view thereof;

FIG. 4 is a front elevational view thereof; and

FIG. 5 is a bottom plan view thereof.

**REEXAMINATION CERTIFICATE
ISSUED UNDER 35 U.S.C. 307**

THE PATENT IS HEREBY AMENDED AS
INDICATED BELOW.

Matter enclosed in heavy brackets [ ] appeared in the
patent, but has been deleted and is no longer a part of the

2
patent; matter printed in italics indicates additions made
to the patent.

5 AS A RESULT OF REEXAMINATION, IT HAS
BEEN DETERMINED THAT:

The single design claim is cancelled.
